UNITED STATES PATENT OFFICE.

CHARLES J. TARRANT, OF CENTRAL, SOUTH CAROLINA.

SPINNING-RING AND BALL-BEARING TRAVELER THEREFOR.

1,372,844.

Specification of Letters Patent. Patented Mar. 29, 1921.

Application filed July 2, 1919. Serial No. 303,124.

To all whom it may concern:

Be it known that I, CHARLES J. TARRANT, a citizen of the United States, residing at Central, in the county of Pickens and State 5 of South Carolina, have invented certain new and useful Improvements in Spinning-Rings and Ball-Bearing Travelers Therefor, of which the following is a specification, reference being had to the accompanying drawings.

This invention relates to spinning rings, and particularly to the travelers thereof.

In the spinning ring as ordinarily constructed, the traveler in its rotation on the 15 ring wears the ring unevenly and the travelers have to be changed from two to three times a month and the rings, because of this uneven wear, last only from two to five years. Of course, uneven wear on the ring 20 due to the operation of the traveler, impedes the smooth and easy action of the traveler and puts an undue drag on the yarn, and further this unevenness which the ring assumes, acts to wear the traveler itself, 25 and because of the unevenness, the traveler wears the ring. Furthermore, and most importantly, the travelers as ordinarily constructed on spinning rings are very liable to fly off. They may fly off in ten minutes' 30 time after they have been put on, or it may be a day before it flies off, but in every case wherever a traveler flies off, the machine must be stopped and a new traveler put on, thus wasting time. Furthermore, the ordinary 35 traveler exerts a relatively hard pull or drag on the yarn and pulls harder when the traverse is at the lower end of its stroke than at the top of its stroke, thus giving an uneven tension on the yarn. This uneven 40 tension is likely to break the yarn, and furthermore, with the present traveler doffing must take place about every two and a half hours.

The general object of my invention is to 45 improve the construction of the ring and traveler so as to secure a traveler which will not wear the ring unevenly, in which the traveler and the ring will last indefinitely because of the even wear, and even 50 this wear is but very slight.

A further object is to provide a traveler which cannot fly off and which will exert an even tension on the yarn at all times, whether the traveler and ring are oppo-

site the upper portion of the bobbin or opposite the lower portion of the bobbin. 55

A further object is to provide a traveler and ring which, due to their construction, will wind the yarn more firmly on the bobbin and thus put more yards of yarn on the 60 bobbin than is possible with the present ring and traveler, thus reducing waste and tangled yarn, reducing the cost of spooling, and requiring that the bobbin shall be doffed only every five hours instead of 65 every two and a half hours, thus eliminating a large number of dosser boys and reducing the cost very materially, both in the actual process of winding the yarn upon the bobbins and twisting it and when the yarn 70 is being woven, inasmuch as yarn which is twisted and wound with my ring and traveler has a much less number of knots and tangles than yarn twisted and wound on bobbins by the usual spinning ring and 75 traveler.

Other objects will appear in the course of the following description.

My invention is illustrated in the accompanying drawings, wherein:—

80 Figure 1 is a transverse sectional view of a spinning ring constructed in accordance with my invention, showing it in its applied position;

Fig. 2 is a top plan view of the spinning 85 ring;

Fig. 3 is a fragmentary vertical section enlarged to show the action of the traveler.

My improved spinning ring and traveler are designed to be used precisely in the 90 same manner as the ordinary ring and traveler, and I have, therefore, thought it unnecessary to illustrate the ring spinning frame and all its parts. The ring is traversed and the bobbin rotated in the usual 95 manner. My invention lies entirely in the detailed construction of the ring and the traveler coacting therewith.

100 By reference to the drawings, it will be seen that my ring is formed in two sections. The section 10 constitutes the holder, as it is known, and is formed to provide an annular base portion 11. Above this base portion the exterior of the ring is increased in diameter, as at 12, and then upwardly 105 and inwardly curved, as at 13. Interiorly, the ring is formed with a face on the base portion parallel to the outer face, and above

this face with an inwardly extending shoulder 14 which then extends upward, as at 15, and then is concavely curved upward, as at 16, the faces 13 and 16 meeting at a relatively acute angle. The ring 17 is formed with a base portion and has practically a uniform interior diameter 18 from the top to the bottom, but the outer face of the ring is reduced above the base portion, then extends upward to form the body of the ring, as at 19, and is formed with a relatively sharp-edged flange 20 at its upper end. The depth of this ring 17 is such that the base portion 18 of the ring will rest upon the shoulder 14 of the holder, while the flange 20 will project toward and be exactly opposite the sharp edge at the upper end of the shoulder. There is thus provided an annular chamber 21 between the ring and the holder with an annular slot leading from the upper end of this annular chamber. The traveler, as illustrated in Fig. 3, consists of a piece of wire bent to form a straight shank 22, which terminates in a head 23 at one end, the other end of the shank being bent to form a laterally disposed loop or eye 24. Loosely surrounding the straight shank and normally bearing against this head is a ball 25 which may be made of hard steel or like material, and which has a diameter greater than the width of the slot between the ring and the holder.

In the use of this device, the holder is, of course, disposed upon the usual ring supporting frame, which is vertically reciprocated by the traverse motion in the usual manner. The yarn *a* extends downward, as usual, from the bobbins mounted on the spinning frame and passes through the eye 24 and then extends to the bobbin *b*. The bobbin is, of course, rotated at a high speed and as a consequence the traveler travels around the ring 17 and acts to twist the yarn and wind it upon the bobbin in the usual manner of a spinning ring. The loop or eye 24 is always upward and inward and the eye 24 is always directed toward the bobbin. The ball 23 is so proportioned to the annular chamber 21 and the slot leading therefrom, that the ball will at all times ride against the side walls of the slot and project slightly upward through the slot, and the shank 22 will not, under these circumstances, come in contact with the side walls of the slot at any point. The only part of the traveler which bears upon the ring and upon the holder is the ball 25, and as this ball is freely rotated relative to the shank 22, it will be obvious that it acts as an anti-friction element and permits the easy travel of the traveler around the ring with a minimum of friction. It is a vital part of my invention that the slot is so located with reference to the ring and holder

that the shank shall project upward and the tension on the yarn shall draw the ball snugly up into this slot, as heretofore described, so that the shank will not touch the side walls of the slot.

It will be noted that my device comprises only two parts, namely the holder and the ring, and that these are very simple and cheaply constructed, and that the traveler simply consists of a loop of wire with a rotatable ball on one end. In the operation of this device, the traveler exerts an even and constant tension at all times, due to the fact that it leans over toward and follows the bobbin as it moves up and down, thereby winding the yarn more firmly on the bobbin than it is possible to do with the ordinary traveler and puts more yards of yarn on a bobbin before the bobbin has to be doffed. This reduces waste and reduces all chance of tangled yarn. Furthermore, with my device, there is no need of a separator, as the yarn will not balloon, as it does with the ordinary spinning ring. Inasmuch as the yarn is wound more firmly upon the bobbin and more yarn can be placed upon a single bobbin than is the case with the ordinary spinning ring, it follows that the bobbins have to be doffed less frequently, thus reducing the number of doffer boys used. In actual practice I have found that by the use of my improved spinning ring, it is only necessary to doff the bobbins once in every five hours, whereas with the ordinary spinning rings, it is necessary to doff the bobbins every two and a half hours. Inasmuch as the machines have to be stopped while the bobbins are being doffed, it is obvious that there is a saving in not only the number of employees required to doff the bobbins, but there is a saving in time, which amounts to a good deal in the course of a day. Furthermore, a very great saving is secured in the fact that these travelers cannot possibly fly off as the ordinary traveler does, with the consequent stoppage and delays. Of course, as before explained, these rings, consequent on there being no friction upon them, will last indefinitely. The ring may be easily disassembled from the holder in order to put in a new traveler whenever required.

In actual practice, it has been found that my traveler will not wear the ring, nor will the traveler be worn to any extent through long periods of time, so that thus a saving is accomplished in the number of travelers used, which is very great in large mills.

I am aware of the fact that a spinning ring has been devised wherein a traveler is used having a shank provided with a rotatable ball, but the ring and traveler are so formed that there is more or less constant wear on the shank of the ring and on the wall of the slot, which would cause the rings to become uneven in a relatively short time.

With my device, the traveler is at all times pulled upward against the slot between the ring and the holder, and is not drawn laterally so far that the shank will bear against the side wall of the slot. Furthermore, my device is very readily assembled and disassembled and consists of but very few and simple parts.

I claim:—

1. In a spinning ring, a holder and a ring proper coacting with the holder and formed to provide an annular chamber, there being an annular slot extending from the horizontal face of the spinning ring into said chamber, and a traveler comprising a shank extending through the slot into said chamber and having an eye at its upper end, and an anti-friction ball rotatably mounted on the inner end of the shank and disposed in said chamber, said slot having a width slightly less than the extreme diameter of the ball, whereby the tension of the yarn passing through the eye will hold the ball into contact with the upper wall of the chamber and projecting partially through the slot to thereby permit free lateral oscillation of the shank.
2. In a spinning mechanism, the combination with a ring rail and a bobbin, of an annular ring holder mounted upon the rail, an annular ring disposed within the ring holder and resting thereon, the ring and holder being cut out to form a circumferential chamber having a relatively wide, annular slot extending into said chamber from the upper face of the holder and ring, the walls of said slot being beveled, a shank extending downward into said chamber, and the upper end of the shank being bent to form an eye, and a ball rotatably mounted upon the shank and disposed within the chamber, the slot having a diameter slightly less than the diameter of the ball, whereby the tension on the yarn passing through said eye will hold the ball against the upper wall of the chamber and projecting slightly through said slot to thereby permit the free lateral oscillation of the shank.
3. In a spinning ring comprising a holder formed to provide a cylindrical portion adapted to seat within a ring rail and having its inner face cut away to provide an annular shoulder and above the shoulder being cut away to form one wall of an annular chamber and having an inwardly extending, tapered flange at its upper end, a ring disposed within the holder and formed to provide a base portion resting upon the shoul-
- der and cut away upon its outer face to form the inner wall of said chamber, the inner wall having an outwardly projecting, beveled flange at its upper end, the two flanges being spaced from each other to define an annular slot extending into the chamber, and a traveler comprising a straight shank extending into the slot and having a diameter relatively small as compared to the width of the slot, the shank at its upper end being bent to form an eye and at its inner end carrying a rotatable, anti-friction ball operating within the chamber, said ball having a diameter slightly greater than the width of the slot, whereby to permit the tension of the yarn passing through said eye to hold the ball in the upper portion of the chamber with a portion of the ball projecting through the slot to thereby permit the shank to have free lateral oscillation to a considerable degree.
4. A spinning ring comprising a holder and a ring proper coacting with the holder and formed to provide an annular chamber and a relatively wide, annular slot leading into said chamber, and a traveler comprising a shank extending through the slot and less in diameter than the width of the slot, a rotatably mounted anti-friction element carried on the inner end of said shank and disposed in said chamber, the outer end of the shank being bent to engage the yarn, the anti-friction member having a width transversely slightly less than the width of the slot and normally bearing against the walls of said slot and projecting partially therethrough, and the shank thereby having oscillatory movement transversely of the slot to a considerable degree.
5. A spinning ring having a circular raceway on its upper face, the raceway having overhanging walls, a holder for the spinning ring, and a traveler moving in the circular raceway and beneath said overhanging walls, the traveler having an upwardly extending shank formed with an eye and being freely oscillatable between the overhanging walls through a relatively large arc in directions radial to the axis of the spinning ring and in the direction of the circular movement of the traveler.

In testimony whereof I hereunto affix my signature in the presence of two witnesses.
